UNITED STATES PATENT OFFICE.

MORITZ ALTMANN, OF CAMDEN, NEW JERSEY, AND JOHN DAVEY, OF PHILADELPHIA, PENNSYLVANIA.

SUSPENDERS.

SPECIFICATION forming part of Letters Patent No. 223,628, dated January 20, 1880.

Application filed October 6, 1879.

To all whom it may concern:

Be it known that we, MORITZ ALTMANN, of the city and county of Camden, State of New Jersey, and JOHN DAVEY, of the city and county of Philadelphia, State of Pennsylvania, have invented a new and useful Improvement in Suspenders, which improvement is fully set forth in the following specification and accompanying drawings, in which—

10 Figure 1 is a face view of a portion of a suspender embodying our invention. Fig. 2 is a view of a detached portion thereof. Fig. 3 is a longitudinal section of Fig. 2.

15 Similar letters of reference indicate corresponding parts in the several figures.

Our invention consists of the button holes or loops of suspenders, made extensible by means of metallic pieces, each of which is constructed of two tubular parts, one of which 20 is immovably secured to one portion of the tab material, and the other is cylindrical and freely incloses the adjacent portion of said material, said portions constituting the termination of the button-hole, whereby said button holes or loops may be opened and closed for various purposes.

25 It also consists of a stop-collar for limiting the reduction or closing of the button-hole and receiving the strain thereon.

30 Referring to the drawings, A represents buttoning-tabs of a pair of suspenders, and B the button holes or loops thereof, each of which is formed by turning up the end of a piece of cord, webbing, or other suitable material against itself and securing said end to the part in contact, for which purpose we employ a clamp, C, consisting of a piece of metal bent into double tubular form, one side or part being preferably conical and rigidly fixed to the end of the tab material, and the other side or part being cylindrical and loosely encircling and protectively inclosing the adjacent portion of said material.

35 To a proper portion of the length of the material there is firmly secured a collar, a, which is adapted to fit an offset, b, on the bottom of the clamp C and form a stop therefor.

40 It will be seen that one portion of the clamp 45 is rigidly connected to the end of the button-

hole material and the other portion slides on the adjacent length of said material, whereby the button-hole may be readily enlarged or reduced, as desired, this feature being serviceable for conveniently applying and removing the button-hole to and from the button, and the reduction or contraction for the closing and security of the button-hole on the button, and, furthermore, adapting the button-holes to buttons of various sizes.

50 The limit of reduction of the button-hole is the stop-collar a.

55 It will also be seen that as the end of the button-hole is fixed to the clamp C and the latter is in contact with the collar a, the button-hole is reliably formed or connected, so as to endure the severe strain to which it is subjected without liability of separation or dismemberment.

60 We are aware that it is not new to secure 70 button-holes of suspenders by means of tubular metallic clamps, and therefore disclaim such feature, broadly; but we are not aware of any clamp formed of two parts, one of which is rigidly clamped to the end of the tab 75 material, and the other slides freely on the adjacent portion of the tab material and protectively incloses the latter portion of wearing action of the other portion.

75 Having thus described our invention, what 80 we claim as new, and desire to secure by Letters Patent, is—

85 1. In combination with a suspender end or tab, the sliding clamp C, consisting of a piece of tubular metal having one side rigidly secured to the end of the tab material and the other side cylindrical and sliding freely on the other length of said material, to form the button-hole loop, substantially as and for the purpose set forth.

90 2. In combination with the tabs A and clamps C, stop-collars a, substantially as and for the purpose set forth.

MORITZ ALTMANN.
JOHN DAVEY.
